United States Patent Office.

ALFRED F. JONES, OF NEW YORK, N. Y.

Design No. 4,949, dated May 30, 1871.

DESIGN FOR A BELLows.

The Schedule referred to in these Letters Patent and making part of the same.

To all whom it may concern:

Be it known that I, ALFRED F. JONES, of New York city, in the county and State of New York, have invented a new and original Design for a Bellows; and I do hereby declare that the following is a full, clear, and exact description thereof, which will enable others skilled in the art to make and use the same, reference being had to the accompanying drawing forming a part of this specification, in which—

Figure 1 represents a plan or top view of my design for bellows.

Figure 2 is a side view of the same.

Similar letters of reference indicate corresponding parts.

This invention relates to a new configuration of bellows, and consists in making the same of oval form—

that is to say, in making the movable top plate oval and fitting the flexible sides to its edge.

A in the drawing represents the upper plate of the bellows;

B are the flexible sides; and

C is the bottom.

The top is of oval shape and is hinged to the bottom, which is of suitable form. The flexible sides are secured to the oval edge of A and form an oval chamber within the bellows.

I claim as my invention—

The design for the oval bellows, as shown.

ALFRED F. JONES.
